ELECTRICAL CONDUCTOR

Honel A. Jackson, Detroit, Mich.

Application March 1, 1943, Serial No. 477,658

4 Claims. (Cl. 173—363)

This invention relates to electrical conducting mechanism consisting of separable, electrically conductive, cooperating sections.

An important object of the invention is to provide a novel connection between the separable sections, which positively assures electrical connection and holds the parts against accidental separation in use.

A further object of the invention is to provide a novel form of conducting mechanism consisting of separable sections, which is constructed of few parts which are easily made and assembled and which can be quickly disassembled for repair and substitution of parts.

In operation the novel connecting means requires only a slight turning movement of one separable section of the conducting mechanism relative to the other, in order to either attach or detach the two sections one from the other. The form of coupling provided by the invention assures an excellent electrical contact with the electric cable leading from the source of current supply.

A novel feature of the present invention is the concealed character of the terminals which complete the electric circuit between the two sections. In use the terminals are protectingly housed within an insulating sleeve and cannot accidentally make contact with outside objects.

The invention illustrated is embodied in an improved electrode holder and also in an improved cable connector. Whether embodied in an electrode holder or a cable connector the connection established between the two sections is simple, positive and efficient.

If embodied in an electrode holder, an important object is to provide a novel form of welding electrode holder which is separable into sections such that the handle portion may be permanently affixed to the end of an electric cable and the electrode gripping portion may be quickly attached and removed from the handle section.

More specifically, an important object is to provide an improved form of electrode holder having a novel means for detachably connecting the electrode gripping portion to the handle portion, and to provide positive means which requires little effort on the part of the operator for holding the two portions against accidental separation while in use.

A further object of the invention, when embodied in an electrode holder, is to provide a holder which is protectingly insulated in such a manner that the holder may be laid down or

accidentally struck against surrounding objects without fear of shorting the circuit and either damaging the work or injuring the operator. As a result the holder may be connected at all times with the source of current supply while in use and there is no need to provide extra switch means for breaking the circuit to the electrode when the tool is laid down or the electrode changed.

10 Various other objects, advantages and meritorious features of the present invention will become more fully apparent from the following specifications, appended claims and accompanying drawings, wherein:

15 Fig. 1 is a longitudinal sectional view through the electrode holder showing the electrode holder section and the handle section joined together in operating position.

Fig. 2 is a longitudinal sectional view through 20 the connected portion of the holder sections at 90° to the position of the parts illustrated in Fig. 1.

Fig. 3 is a view, partly in section and in smaller scale, of the two sections of the electrode holder, showing them in slightly separated condition,

25 Fig. 4 is a cross sectional view along line 4—4 of Fig. 1, and

Fig. 5 is a sectional view along line 5—5 of Fig. 1.

Fig. 6 is a longitudinal sectional view through 30 the invention embodied in a cable connector.

Fig. 7 is a sectional view on line 7—7 of Fig. 6.

This application is a continuation in part of my application Ser. No. 453,173, filed August 1, 1942.

In the electrode holder embodiment of the invention, illustrated in Figs. 1 through 5, an electrode holder of the general type shown in my Patent No. 2,003,196 is used. It is understood that the present invention is not restricted to this type of holder, but may be incorporated in other forms of holders and modified to suit different conditions.

Referring specifically to the drawings, and first to the electrode holder embodiment, the holder comprises two separable sections or portions. One section grips the electrode and may be referred to as the electrode gripping or holding section. The other section is grasped by the hand of the operator and may be referred to as the handle section. The two sections in separable condition are shown in Fig. 3; the electrode gripping section being generally indicated at 10; the handle section at 12. In use the two sections are joined together end-to-end and electric connection made with source of current supply.

of jaw members 14 and 16. They are pivotally connected together by a transverse pin 18. In the forward ends of the jaw members are prooved plates 20-20 which face toward one another and serve to grip an electrode therebetween. These plates are urged together by a coiled spring 22 located on the other side of the pivot 18 and mounted in telescoping insulating cups 24-26.

Both jaw members are preferably provided with insulation covers of the type described and claimed in my aforesaid patent. These insulation covers are preferably in the form of separate pieces of channel formation. Two such pieces are provided on jaw member 14 and are indicated at 28 and 30. Similarly two insulation pieces 32 and 34 are provided on jaw members 16. As shown best in Fig. 3, these insulation covers extend the length of the jaw members and the overhangs provided by their channel formation protect the sides of the jaw members. As will be more particularly brought out hereinafter, in connection with the holder as a whole, these insulation pieces enable the holder to be laid down or accidentally brought into contact with surrounding objects without fear of contacting with grounded metal.

The handle section generally indicated at 12 comprises an outside body or sleeve 36 of insulation material, preferably of tubular formation. Enclosed inside this sleeve is a member 38 of electric conductive material. This member is disposed intermediate the ends of the sleeve, which are open as shown, and preferably provided with circumferentially spaced longitudinal ribs 40 which engage the inside surface of the sleeve and form longitudinal passages therebetween for the circulation of air.

Member 38 serves as an electric connection between a source of current supply and the electrode holder section when the holder is in completely assembled condition. It is provided on the side facing the rear end of the handle with a circular recess 42 in which the terminal end of an insulated electric cable 44 is received. Preferably the end of the cable is permanently fixed in the recess by solder or other suitable means. The opposite forward end of the member 38 is provided with a conical recess or bore 46. The bore extends for a considerable depth and the walls thereof taper at a relatively slight angle. Receivable in the bore is a conical tapered terminal end 48 of the jaw member 16. The terminal end 48 is relatively long and correspondingly tapered to slidingly fit within the bore when fully inserted to be frictionally wedged therein.

Novel means is provided for positively coupling the two sections of the holder together and holding the same in this condition against accidental separation. This means provides a quick and easy means of connection and disconnection and is protectingly and inconspicuously concealed within the tubular handle. To accomplish this end the jaw member 16 is provided immediately adjacent to the base of the tapered end 48 with a radially enlarged collar 50 forming an integral part of the jaw member. The outside dimension of the collar is slightly less than the internal diameter of the sleeve 36 and as shown in Fig. 4, longitudinal ribs 52 are provided, which correspond in position to certain of the ribs 40 on member 38 and bear against the inside surface of the forward end of the sleeve. This collar is provided on its forward side, or the side opposite to the terminal end 48, with an inclined face in the form of a crown cam 54. At the low end 75

of the cam surface is a longitudinal slot 56 in the collar which opens on the terminal side thereof.

Forming part of the handle section of the holder is a novel means which when the two sections are joined together, will be in position to ride up the inclined cam surface and positively lock the two sections against longitudinal separation. This means takes the form of an element which is preferably detachable for repair and replacement. As shown, the element is preferably a strip 58 of flat metal stock or similar composition, which extends the length of the electrical connection 38 and between the outside surface thereof and the inside of the sleeve 36. The ends of this element or strip are inturned to form flanges 60 and 62. The flange 60 at the rear end is adapted to abut the rear end of the connector member 38. The flange 62 at the forward end is adapted to ride upon the cam surface 54 and its contacting surface is slightly rounded as shown in Fig. 2, to facilitate this movement. The forward end of the strip projects in advance of the member 38 and when the two sections are first brought together the projecting end of the strip passes through the slot 56 to the forward side of the cam. It is evident that a slight turning movement of one section relative to the other will cause the flange 62 to ride upon the cam surface.

The locking element or strip 58 is preferably readily detachable from the handle section. This is accomplished in a highly convenient way by utilizing the same means which secures the member 38 in the sleeve 36 against movement for also securing the strip 58 in position. As shown, fastening means in the form of a screw 64 extends transversely through the sleeve, strip and into the central portion of member 38. All three parts are thus secured together and rotate as a unit.

Preferably, the hole 66 in the strip through which the screw 64 extends is made slightly oversize to allow a small longitudinal play of the strip, 45 and also to provide adjustment if it is necessary to repair it during the life of the holder. The oversize hole 66 relieves the screw 64 of any lateral pressure which would be otherwise imposed upon it if the hole were the same size as the screw. Loads imposed on the strip as its forward flange 60 rides up the cam, are transferred directly to the coupling member 38 by the rear flange 60. If the strip should be damaged by the bending or breaking of one of the flanges, it 55 is easy to disassemble the parts and repair the strip. If one of the flanges breaks off a new one can be formed, and if necessary the remaining flange reduced in height to provide sufficient metal for forming the new flange. The oversize hole 66 permits shifting of the position of the repaired strip on the member 38 to predispose the flanges in proper operating position. These repair facilities are especially advantageous for large industries using many electrode holders and where on the average a small percentage of all the holders are in need of repair. This can be performed by the repair department at no expense and little delay.

The coupling member 38 is constructed in a highly convenient way to hold the strip against lateral displacement. As shown in Figs. 2, 3 and 5 what would otherwise be the bottom longitudinal rib is divided into two slightly spaced apart ribs 40-40, forming a groove in which the strip 58 may be slidably fitted. These ribs, to-

gether with the rear flange 60 and the screw 64 act to hold the strip in operating position.

For optional use a second locking means may be provided. As shown in Fig. 1 the tapered terminal end 48 may be provided with an arcuate recess 68 on one side. A set screw 70 is threaded in the wall of the bore 46 of the coupling member 38 and upon threaded advancement is adapted to enter the arcuate recess. Preferably the bottom of the recess opposite to the set screw is upwardly inclined toward the terminal end, in order to provide a wedging action tending to advance the terminal end further into the bore as the set screw presses thereon.

Considering now the cable connector embodiment of the invention, which is illustrated in Figs. 6 and 7 of the drawings, it will be noted that the female connection is identical with the handle section of the electrode holder. The male connection is similar to the jaw section of the electrode holder. Considering specifically the construction of the cable connector, each section includes a cylindrical sleeve of suitable insulation material. The sleeve which forms a part of the female section is indicated by the numeral 90 and positioned within this sleeve is an electrically conductive member 92. This member may be secured in the sleeve by a set screw 94. An insulated cable 96 has its terminal portion 98 socketed within a cylindrical recess in one end of the member 92. This attachment may be a permanent one as by soldering the terminal end of the cable to the end 92. The cable may lead from a suitable source of electric power. The opposite end of the member 92 is provided with a tapered conical socket 100. This socket portion of the member 92 terminates spaced from the end of the sleeve 90. A connecting screw 102 is carried by the member 92 and may be threaded into or out of the socket 100 as shown in Fig. 6.

The cooperating connection also comprises a cylindrical sleeve indicated as 104 which is formed of suitable insulation material. Within this sleeve is positioned an electrically conductive member 106, which member may be held therein by a set screw 108. This member is provided with a cylindrical recess in one end wherein is received the terminal end 110 of an insulated electrical cable 112, as shown in Fig. 6. Such terminal of the cable may be soldered within the conductive member 106.

The opposite end of this member 106 is provided with a terminal portion 114 which is of conical shape and of a size to be snugly received within the socket 100 of the member 92. The connection between the two sections of the cable connector is established in the same manner as the connection between the handle sections and the jaw section of the electrode holder. The conductive member 106 is provided with a circumferential shoulder 116 which corresponds to the shoulder 50 on the conductive jaw element 16 on Fig. 1. The circumference of the shoulder 116 is such that it is readily received within the open end of the sleeve 90 as shown in Fig. 6. That face of the shoulder which is adjacent to the main body of the element 106 is shaped in the form of a crown cam 118. At the low end of the crown surface is a longitudinal slot through the shoulder which is not shown in Figs. 6 and 7, but Fig. 2 shows the corresponding slot 56 in the electrode holder embodiment of the invention.

That portion of the female section which engages the cam 118 is in the form of a flat metal

strip 120 which extends the length of the member 92 and is disposed between the outside surface thereof and the inside of the sleeve 90 as shown in Fig. 6. The ends of this strip are inturned as at 122 and 124. The end 122 overlaps the cable end of the member 92. The end 124 is adapted to engage the cam 118. This strip 120 is apertured as at 126 and the screw 94 extends through this aperture as shown in Fig. 6.

The flange 124 is of a size to pass through the longitudinal slot through the cam and is adapted to ride upon the cam surface so that upon relative rotation of the two sections the engagement of the flange 124 with cam 118 will draw the element 106 and 92 tightly together forming an effective electrical contact and secure mechanical connection. The crown cam 118 extends only partially circumferentially about the terminal 114. It is apparent that when the connection is established 15 the conducting parts are disposed entirely within 20 the sleeve 90. It will be noted that, as in the embodiment illustrated in Figs. 1 and 2, the conical 25 terminal 114 is cut away as at 130, providing an arcuate recess adapted to receive the round end 30 of the connecting screw 102. This recess is so shaped that as the screw 102 is threaded into it against the tapered bottom of the recess, the conical terminal 114 of the member 106 is drawn snugly into the socket of the member 92. This forms an additional securing connection to maintain the two sections together and to urge them tightly together.

Fig. 7 which is taken on the section line 7—7 Fig. 6 illustrates a preferred cross section for 35 the elements 102 and 92. It is shown in connection with the element 106, but the element 92 is similarly shaped. This cross sectional shape is the same as that shown in connection with the element 38 of the electrode holder. 40 The main body of the member 106 or 92, as the case may be, is provided with long extending relatively narrow ribs 128 which engage the interior surface of the sleeve and space the major portion of the periphery of the member from 45 the sleeve providing air cooling space about the member within the sleeve.

It will also be seen that the insulated cable that is secured to the outer end of the member 92 and the insulated cable that is secured to the 50 outer end of member 106 is of such a size as to provide an air space thereabout within the sleeve which would permit the admission of air for cooling. This structure is the same as that shown in the electrode holder Figs. 1 and 2.

55 It is apparent that in use the jaw portion of the electrode holder may be removed from the handle portion which is permanently attached to a cable section and an additional cable section may be attached in lieu of the jaw portion. Each cable section adaptable for insertion in a line would have a male member at one end and a female member at the opposite end. The jaw portion of the electrode holder might then be secured to the opposite free end of the 60 cable section that had been inserted. It is apparent that the connection formed between the two sections shown in Fig. 6 is in every way the same as the connection formed between the two sections shown in Fig. 1 and the more complete 65 description of the structure shown in Fig. 1 is applicable to the structure shown in Fig. 6.

What I claim:

1. Conducting means comprising, in combination a pair of separable sections, one section including a member of electrically conductive ma-

terial provided with outside insulation, the other section including an outside covering of insulation material and an inside member of electrically conductive material, one of said members provided with a longitudinal extending conical bore, the other member provided with a longitudinal extending conical part of a size and shape to be tightly received within said bore, an inclined cam on one of said members inclining longitudinally thereof and away from the other member, and means carried by said other member adapted to overlap upon said cam when said conical part is tightly received within said bore, and to ride up the inclined fall of the cam when the two sections of the holder are rotated relatively to one another about their longitudinal axes releasably securing said sections together.

2. Conducting means comprising, in combination a pair of separable sections, one section including a member of electrically conductive material provided with outside insulation, the other section including an outside covering of insulation material and an inside member of electrically conductive material, one of said members provided with a longitudinal extending conical bore, the other member provided with a longitudinal extending conical part of a size and shape to be tightly received within said bore, said member having the conical part provided adjacent to the base of said part with an arcuate segmental portion provided on the side remote from said conical part with a crown cam extending partly circumferentially thereabout, said member having the conical bore provided with a part projecting beyond said bore and adapted to overlap upon said cam when said conical part is tightly received within said bore, and to ride up the inclined fall of the cam when the two sections of the holder are rotated relatively to one another about their longitudinal axes releasably securing said sections together.

3. Conducting means comprising, in combination a pair of separable sections, one section including a member of electrically conductive material provided with outside insulation, the other section including an outside covering of insula-

tion material and an inside member of electrically conductive material, one of said members provided with a longitudinal extending conical bore, the other member provided with a longitudinal extending conical part of a size and shape to be tightly received within said bore, said member having a conical part being provided adjacent to the base of said part with a crown cam inclining longitudinally thereof and away from the other member, a finger-like element secured to said other member within the insulation material and projecting beyond the conical bore of said member and having a terminal part adapted to overlap upon said cam when said conical part is tightly received within said bore, and to ride up the inclined fall of the cam when the two sections of the holder are rotated relatively to one another about their longitudinal axes releasably securing said sections together.

4. Conducting means comprising, in combination a pair of separable sections, one section including a member of electrically conductive material provided with outside insulation, the other section including an outside covering of insulation material and an inside member of electrically conductive material, one of said members provided with a longitudinal extending conical bore, the other member provided with a longitudinal extending conical part of a size and shape to be tightly received within said bore, an inclined cam on one of said members inclining longitudinally thereof and away from the other member, and means carried by said other member adapted to overlap upon said cam when said conical part is tightly received within said bore, and to ride up the inclined fall of the cam when the two sections of the holder are rotated relatively to one another about their longitudinal axes releasably securing said sections together, the conical part of the one member provided with a recess in its conical face having an inclined surface, and means carried by the other member extending into the conical bore thereof adapted to be projected into said recess against said inclined surface.

HONEL A. JACKSON.
